(57) **CLAIM**

The ornamental design for a portion of a display screen with a graphical user interface, as shown and described.

DESCRIPTION

FIG. 1 is the front view of a first embodiment of a portion of the display screen with a graphical user interface in a first appearance state.

FIG. 2 is the front view of a second embodiment of a portion of the display screen with a graphical user interface in a first appearance state.

FIG. 3 is the front view of a third embodiment of a portion of the display screen with a graphical user interface in a first appearance state.

FIG. 4 is the front view of a fourth embodiment of a portion of the display screen with a graphical user interface in a first appearance state.

FIG. 5 is the front view of the second embodiment of a portion of a display screen with a graphical user interface in second appearance state.

FIG. 6 is the front view of the second embodiment of a portion of a display screen with a graphical user interface in a third appearance state.

FIG. 7 is the front view of the second embodiment of a portion of a display screen with a graphical user interface in a fourth appearance state.

FIG. 8 is the front view of the second embodiment of a portion of a display screen with a graphical user interface in a fifth appearance state; and,

FIG. 9 is the front view of the second embodiment of a portion of a display screen with a graphical user interface in a sixth appearance state.

The broken lines shown in the drawings illustrate the display screen and portions of the graphical user interface and form no part of the claimed design.

1 Claim, 8 Drawing Sheets
